UNITED STATES PATENT OFFICE.

JOSEPH M. SCHUTZ, OF CHICAGO, ILLINOIS, ASSIGNOR, BY MESNE ASSIGNMENTS, TO STANDARD RIBBON MACHINE COMPANY, OF CHICAGO, ILLINOIS, A CORPORATION OF ARIZONA.

RIBBON-INKING MACHINE.

1,115,341.

Specification of Letters Patent. Patented Oct. 27, 1914.

Application filed March 17, 1913. Serial No. 754,898.

To all whom it may concern:

Be it known that I, JOSEPH M. SCHUTZ, a citizen of the United States, and a resident of Chicago, county of Cook, and State of Illinois, have invented certain new and useful Improvements in Ribbon-Inking Machines, of which the following is a specification.

My invention relates to improvements in inking devices and has particular reference to improvements in ribbon inking machines.

The object of my invention is to provide a simple device which shall render it comparatively easy to quickly ink a ribbon of any width, within the capacity of the device, and to any intensive or depth of color.

A further object of my invention is to provide a device of simple construction which shall be easily adjustable to ink ribbons of different widths and to different depths of color.

A further object of my invention is to provide a ribbon inking device which can be readily, quickly and easily adjusted to properly align the ribbon supply spool and rewind spool to accommodate ribbons of different widths and spools of various lengths and having central openings of different diameters or sizes.

A further object of my invention is to provide a ribbon inking device of such simplicity of construction, adjustment and manipulation, that it shall be a practical office device for general office use, and capable of being used successfully by the usual office employees who are not especially skilled in such matters.

A further object of my invention is to reduce the cost of inked ribbons, particularly for use on type-writing, duplicating and multiple printing machines, to reduce the wear and tear on such machines and ribbons, and particularly to reduce the effort of the machine manipulator in producing well written and evenly inked work.

My invention resides in a ribbon inking machine, having rollers between which the inked ribbon is passed and by which it is pressed, means for producing a pressure to correspond with the width of the ribbon and the depth of the color desired, means for causing the ribbon to be automatically re-

wound upon a proper spool, and means for alining the spool from which the ribbon is being unwound with the driven spool upon which the ribbon is being wound.

My invention also consists in the several arrangements and co-ordinations of devices and parts, and in the features of construction by means of which the above and other objects are attained, and all as hereinafter described and particularly pointed out in the appended claims.

My invention will be more readily understood by reference to the accompanying drawings forming a part of this specification and in which:

Figure 1 is a top plan view of a ribbon inking machine embodying my invention in one form; Fig. 2 is a side elevation of a machine; Fig. 3 is a longitudinal section of the machine on the line 3—3 of Fig. 1; Fig. 4 is a transverse vertical section of the machine on the line 4—4 of Fig. 1; Figs. 5, 6, and 7 are detailed views showing various forms of spools upon which the ribbon is wound; Fig. 8 is an end elevation of the driving spindle; and Fig. 9 is a diagrammatical sectional view illustrating the adjustments of the spool driving and holding centers to accommodate the various widths of ribbons and shapes and sizes of spools.

The extensive use of typewriting, multiple printing and duplicating machines has created a large demand for inked ribbons. These ribbons are usually made of silk or similar material and are soaked in ink and otherwise prepared for use upon the various machines. The operation of the machines removes some of the ink from the ribbons to the material being printed upon and consequently from the moment that the ribbons are put into use they gradually decrease in the quantity of ink which they contain and the depth or intensity of the color of the printed result gradually lessens.

In the operation of a typewriting machine it is quite a common practice to graduate the force of the blow, in striking the character, in accordance with the quantity of ink on the ribbon, that is, as the ribbon becomes more and more free of ink the force of the stroke necessarily has to be increased in order to make a clear legible copy. This

increase in the force of the stroke necessarily produces a greater and faster wear of the ribbon and tends to deteriorate it rapidly. If the ribbon is not operated constantly and the ribbon remains upon the machine for any length of time, another cause operates to deteriorate the ribbon, viz., the ink on the ribbon dries out. The ribbon, of course, serves as a vehicle for the ink and in order that it may best serve this purpose it should be reinked at intervals in order to prevent the deteriorating effects above mentioned. Another feature which is of value in this connection is that in business, as at present conducted, many facsimile typewritten letters are used in which it is necessary to insert upon a typewriting machine the individual superscription and address and for this purpose it is necessary, for the best result, to use a ribbon on the typewriting machine of a color and intensity which corresponds most nearly to the color of ink which the fac-simile typewriter letter has been printed.

My invention is particularly useful in rapidly producing inked ribbons of the desired shade or intensity of color, of rapidly and cheaply re-inking ribbons from which some of the ink has been used, and is particularly intended to supply the need of a machine which can be built and sold at a relatively low price, and which is intended to be installed in an office having a number of typewriters or other similar printing machines which employ inked ribbons in the production of the printed sheets.

It will be understood that an inked ribbon which is used for a short time and then re-inked will not only last a very much longer time itself, but will result in a more even and uniform quality of finished work being produced with less effort on the part of the operator and with less wear and tear on the machine. One of the features which serve to make my improved inking machine of value is the easily adjustable devices which the machine contains of causing it to properly operate upon ribbons of various widths, and ribbon spools having different central or axial openings, together with the ease by which the desired depth or intensity of color can be produced.

My invention as depicted in the drawings comprises a fixed pressure roll 1, and an adjustable pressure roll 2 mounted in a suitable frame having vertically arranged side members 3 which are rigidly mounted in position upon a suitable base 4. The side frames are provided with oppositely projecting parallel extensions 5 and 6 upon which are carried respectively the ribbon supply spool 7 and the ribbon re-wind spool 8. These spools, which will be described later, are carried upon adjustable pivot centers or bearings. As illustrated in the draw-

ings, I preferably arrange the pressure rolls 1 and 2 one above the other. I fix roll 1 at the bottom and I provide means for moving the upper roller bodily up and down, and for forcing it against the lower or fixed roller with such a pressure that the ribbon which is passed between the rollers will have all superfluous ink removed therefrom. Beneath the pressure roller and between the side frames 3 I place an open-topped ink-well 9 and I cause the ribbon, in its passage from the supply roller to the re-wind roller, to be immersed in the ink contained in the ink-well before it reaches the pressure rollers. This ink-well is of a size 80 to fit between the side frames 3 and it rests upon the base 4.

The lower roller 1 is mounted on a shaft 10 to rotate therewith, and the shaft is rotatably mounted in suitable fixed bearings 85 11, 11, formed in the side frames 3. The upper roller 2 is provided with a similar shaft 12, and instead of mounting this shaft in fixed bearings, I mount it in vertically movable bearings 13, 13, and I provide 90 means for moving these bearings up and down for applying pressure to the ribbon passing between the rollers, and for separating the rollers at times when it is desired to pass the end of a ribbon between 95 them when starting the machine into operation. For the purpose of moving these bearings 13 up and down and thus adjusting the position of the upper roller relatively to the lower roller, I provide a rock 100 shaft 14 which is substantially parallel with the axis of the roller and is arranged above them, this rock shaft is mounted in a separator or spacer member 15, which spaces the top ends of the side frames 3 apart 105 and this spacer is held in position by bolts 16 which pass through the spacer and through the two side frames. The shaft 14 is mounted in a suitable bearing opening 17, formed in the spacer member 15, and is 110 provided on each end with a longitudinally extending eccentrically arranged pin 18, the pins on the two ends being in axial alignment. I connect respective pins 18 with respective ends of the shaft 12 by means of 115 connecting rods 19 which are adjustable in length, each of these connecting rods consists of an upper bearing 20 adapted to fit upon one of the pins 18, a lower bearing 13 fitting the shaft 12, and a right-and-left hand threaded connecting member 22 which screws into each of these bearing members, consequently at times when it is desired to adjust the length of the connecting rod the connecting threaded member is rotated in 120 one direction or the other, to shorten or lengthen the rod. As shown in Figs. 2 and 3, each frame 3 is provided with a slot 19' to accommodate the connecting rods 19, and I make the lower bearings 13 to fit smoothly 130

between the side walls of these slots so that as the upper roll 2 is moved up and down through the medium of the connecting rods the roll is held in its true parallel position relatively to the lower fixed roll 1. The connecting rods 19 are held upon the eccentric pins 18 by any suitable means such as the cotter pins 18' which are inserted through suitable holes provided in the outer ends of the eccentric pins. When the rock shaft 14 is oscillated the upper roll 2 is raised and lowered through the connecting rods 18, and I provide means whereby the rock shaft can be quickly rotated through about 180 degrees, as shown in dotted line in Fig. 3, whereby the upper roll may be quickly lifted to about one-eighth of an inch, thus quickly separating the rolls sufficiently to permit the passage of the end of the ribbon or to permit the passage between the rolls of any metallic hook or clip which may be fastened upon a ribbon which is to be re-inked. This means of rotating the rock shaft 14 comprises a centrally arranged lever 23 which is mounted in a transverse opening 24 in the central portion of a rock shaft and the spacer member 15 is provided with a central slot or opening 25 which permits the movement of the rod 23 from one position to the other and which also co-operates with the rod to prevent end-wise movement of the rock shaft 14. Normally the outer end 26 of the rod 23 extends substantially horizontally and for the purpose of adjusting the pressure upon the ribbon between the rolls I provide a movable weight 27 which is adapted to hang upon the rod 23 and be secured in its adjusted position thereon by means of a set screw 28. For the purpose of quickly adjusting the pressure upon the ribbon to correspond with certain predetermined results, I provide certain markings 29 on the rod 23 for facilitating the placement of the weight. As indicated, I have arranged three groups of markings, and each group indicates three separate positions of the weight, and I preferably provide weights of such a size that a single weight serves for several different widths of ribbon. As indicated in the drawings, the weight 27 is so placed as to give a medium depth of color upon a ribbon substantially one-half inch wide as it is placed on the middle line of the middle set of markings. This same weight, if placed nearer the outer end of the rod 23, would serve to give a pressure sufficient to cause the ribbon to be inked with the least amount of ink, and if placed nearer to the rock shaft 14 it would produce only pressure enough to leave sufficient ink on the ribbon to cause it to provide printing of the deepest or greatest intensity desired. Each group of markings serves for several widths of ribbon, the weight having to be adjusted for each width

of ribbon which a machine is inking and for each degree of intensity or depth of color desired.

For the purpose of driving the rolls 1 and 2, I preferably provide a shaft 30 extending transversely and arranged beneath the lower roll, one end mounted in suitable bearings 31 in the frames 3, 3. Upon one outer end of this shaft I mount pinion 32 and upon adjacent ends of the shafts 10 and 12 I provide gear wheels 33 adapted to mesh together and the lower one arranged to mesh with the pinion 32, and upon the same end of the shaft 30 I provide a hand crank 34 by which the shaft 30 may be rotated and through which the medium of the rolls 1 and 2 are driven. The outer end of the shaft 30 carries a belt pulley 35, which is adapted to drive the re-wind roll in a manner to be described.

In one of the parallel projections 6 of the frames 3 I rotatably mount a driving center or head 36 which is arranged axially parallel with the rollers and is mounted in a suitable bearing 37. It carries upon its outer end a belt pulley 38 arranged in alinement with the pulley 35 on the shaft 30, and power is transmitted from the pulley 35 to the pulley 38 preferably by means of a spiral wound wire belt 39 trained over these two pulleys. The driving head 36 is provided with a conical centering end 40 which is flattened on three sides providing it with three radially extending driving edges 41, and this head is relatively large in diameter. This head is adapted to center and drive re-wind spools 42 of differing dimensions and shapes and having central axial openings of different sizes. The different makes of type-writing machines for ribbons of different widths and the spools upon which these ribbons are wound are of different sizes, shapes and dimensions. One of the essential features of a machine which is to be useful for re-inking typewriter ribbons is that it shall accommodate these ribbon spools which vary in dimensions and shapes. As indicated in Figs. 5, 6 and 7 I have shown several different forms of these re-wind spools 42. The spool shown in Fig. 5 has a very small central opening and consequently the driving center enters but a short distance into the spool. The form of spool shown in Fig. 6 has a larger central opening 43, and the spool is shown as being considerably wider on its face than the spool shown on Fig. 5. The spool shown in Fig. 7 has a still larger central opening and consequently the center enters still farther within this spool. In Fig. 9 I have indicated, by means of the dotted lines 4, 4, the relative positions which the edge of the ribbon would occupy in conjunction with the several spools shown in Figs. 5, 6, and 7. It will be seen that the edge 45 of the ribbon varies in its position

transversely of the machine and in relation to the driving center 36, which is fixed transversely of the machine. For the purpose of holding the spools upon the driving center 36, I provide an adjustable smooth conical center 46 in axial alinement with the center 36 and adjustably mounted in the extension 6 of the opposite frame 3. This center is carried upon the inner end of a screw 47 mounted in a suitably threaded opening 48 in the frame 3 and can be quickly adjusted from and toward the fixed center 40 to accommodate and properly support spools of different sizes. In mounting a spool upon the center 36 it is forced upon the center 36 by means of the adjustable center 46 until the driving edges 41 bite into the material of the spool sufficiently to drive it and then the center 46 is drawn back just sufficiently to permit the drive center 36 to rotate this spool freely, the center 46 is then fixed in its adjusted position by means of the thumb nut 49 which clamps the threaded rod 47 against rotation.

25 At the outer ends of the extensions 5 I mount a pair of smooth conical centers 50 and each of these centers is similar to the smooth center 46 at the opposite ends of the machine, that is they are arranged in axial alinement and are parallel with the axes rolls 1 and 2, and they are both capable of being adjusted transversely of the machine.

When the inked ribbon is being wound upon the flanged re-wind spools it is usually unnecessary to guide the ribbon in any other manner than as described, but when spools which have no end flanges are used, such as shown in Fig. 6, it is necessary to guide the ribbon between the pressure rolls and the re-wind spool. For this purpose I provide a stationary transverse shaft or rod R¹, mounted in the side frames 3 and arranged between the re-wind spool and the pressure rolls in the path of the ribbon. I provide two adjustable collars or flanges R², mounted on this shaft and held in their adjusted positions by any suitable means such as set screws R². When adjusting the machine to ink a certain size of ribbon and especially 50 one which is to be wound upon a spool which has no flanges, the adjustable flanges R² are loosened and moved out of the way and when the ribbon has been properly connected from the supply spool to the re-wind spool the flanges R² are moved into contact with the opposite edges of the ribbon and secured in adjusted positions.

My machine is capable of being used for inking a new ribbon, that is one which has 60 not been inked before, and this new ribbon is usually supplied in a very large single layer roll as shown at 51. This roll is usually supplied with a wooden spool of a length equal to the width of the ribbon, and

in Fig. 9 I have illustrated the adjusted positions of the centers 50 to hold the ribbon spool 52 in line with the re-wind spool 42 held at the other end of the machine on the driving center 36.

My improved machine is particularly adapted for use in re-inking partly used typewriter ribbons, and when used for this purpose the partly used ribbon which is to be inked and which is wound on the spool as it is taken from the typewriting machine, is inserted in the inking machine between the adjustable centers 50 in place of the supply spool shown in the drawing and a similar typewriter ribbon spool is mounted at the other end of the machine to receive the ribbon after it is inked. In this manner the partly used ribbon is transferred from one spool to a similar spool and in being transferred is re-inked. The process is very simple, very easily done and the manipulation of the ribbon is reduced to a minimum.

For the purpose of causing the ribbon A to be immersed in the ink, I provide a rectangular removable frame 53 which is arranged between the side frames of the machine and is adapted to project downwardly into the ink-well 9. This frame has side bars 54 connected together by an upper end bar 55 and a lower end bar 56. This frame is mounted in position between a rigid conical center 57 carried by one of the frames 3 and an adjustable conical center 58 carried by the opposite frame 3 and adapted to be secured in position by means of a thumb nut 59. This frame 53 substantially fills the space 95 between the two frames 3 of the machine, and the upper end bar is in the form of a cylinder and adapted to serve as a guide which supports the ribbon in its passage from the supply spool 52 to the lower bar 56 105 of the frame 53. The ribbon is adapted to pass downwardly from the upper bar 55 between the side bars 54 of the frame 53 around the lower cross bar 56, which is also in the form of a cylinder, and thence up again to 110 the pressure rolls between which it then passes at times when a short ribbon is being placed in the machine for inking, or at times when the new supply spool is being mounted, the frame 53 is loosened from its position 115 and raised out of the machine when the ribbon A can be properly threaded into its relative position, thereafter the frame 53 is lowered into place, its lower end entering the ink well and then the frame is secured in 120 position between the conical centers.

At times when the ribbon is being threaded through the machine, the upper roll is raised to its upper position and the ribbon having been threaded through the frame 53 125 and between the rolls 1 and 2, is thence carried to the re-wind spool and secured thereto in any suitable manner. Thereafter the

weighted lever 23 is turned to its operative position to press the roll 2 down upon the ribbon and then when the rolls are rotated in the direction of the arrows on Fig. 2 by means of the handle 34, the pressure upon the ribbon causes the ribbon to be drawn from the supply spool 52 down around the lower bar 56 of the frame 53 and through the ink and between the rolls 1 and 2. At the same time the belt 39 rotates the driving head 40 and causes the ribbon, which passes the pressure rolls 1 and 2, to be re-wound on the re-wind spool. It is to be noted that as the ribbon is wound on to the re-wind spool this spool will continually re-wind at a faster and faster speed relatively to the movement of the ribbon between the pressure rolls and to compensate for this variation in movement, the belt 39 slips upon its pulleys. I proportion the pulleys in such a manner that even when the re-wind spool is nearly empty it will take up all the slack of ribbon which is passed between the pressure rolls. It will now be clear that by means of my machine I can ink ribbons to any desired color, simply by placing the desired color of ink in the ink-well 9, or by having ink-wells already prepared and filled with the desired color of ink, and replacing one ink-well holding one color of ink with another ink-well holding the desired color of ink.

One of the most valuable features of my machine resides in the ease with which I can produce the desired depth or intensity of color on the ribbon being inked simply by adjusting the weight 27 to the desired position on the rod 23, or by replacing the weight 27 by a weight weighing more or less, as may be desired.

As many modifications of my invention will readily suggest themselves to one skilled in the art, I do not limit or confine my in-

vention to the specific structures herein shown and described.

I claim:

1. In a ribbon inking machine a pair of parallel pressure rolls between which the ribbon passes after it has been inked, a shaft arranged parallel with the pressure rolls having an eccentric at each end, a central journal at each end of one of said rolls, a connecting rod, connecting each said journal with a respective eccentric on said shaft, a lever projecting from said shaft, a movable weight on said lever adapted to force said rolls together to produce pressure on the ribbon, said weight being adjustable, from and toward the shaft to vary the pressure.

2. In a ribbon inking machine a pair of pressure rolls geared together for rotation, and arranged one above the other, a power shaft located below the lower roll and carrying a gear for driving the rolls, means for moving the upper roll up and down comprising a shaft arranged above the upper roll, aligned eccentric pins on the ends of the upper shaft, movable bearings in which the upper roll rotates, adjustable connecting rods connecting the eccentric pins with respective movable bearings, a lever carried by said upper shaft and a weight on said lever, said lever being movable from a horizontal position in which the weight operates to press the rolls together to a substantially vertical position, whereby the upper roll is separated from the lower roll.

In testimony whereof, I have hereunto set my hand, this 15th day of March, 1913, in the presence of two subscribing witnesses.

JOSEPH M. SCHUTZ.
